FIRE ALARM AEROTUBE APPARATUS

William J. Kleinknecht, Garden City, N. Y., assignor to American District Telegraph Company, Inc., Jersey City, N. J., a corporation of New Jersey

Application June 30, 1938, Serial No. 216,671

9 Claims. (Cl. 297—3)

The present invention relates to an improvement in a device for fire alarm systems, and more particularly to an alarm initiating, aerotube assembly.

5 One outstanding feature of the present arrangement lies in the manner in which an elongate length of aerotubing is condensed into a small compact coil, in contradistinction to the customary method of installing such aerotubes, 10 by stringing them longitudinally, along mouldings, in a protected room, or around the upper sections of the walls of such rooms.

The condensed coil arrangement of the tubing herein disclosed permits of the provision of a 15 large amount of tubing in a small space, thereby to obtain greater atmospheric surface exposure and greater speed of operation, during critical room temperature change periods, and, due to its compactness, is more economical to install, as 20 will hereinafter be noted.

A further feature of advantage is that, in the tubular coil arrangements herein shown, the tubing is more fully exposed to the surrounding atmosphere, there being substantially very little 25 shielding of the tubing, such as happens in the present, earlier methods of moulding or wall installations, and thereby more surface area of the aerotube is presented to the atmosphere. A further feature in this latter respect is that the 30 aerocoils are mounted in skeleton supports a sufficient distance from the wall or ceiling and the coils are thus substantially surrounded by, and subjected to, the free circulation of air currents thereabout, due, in part, to the cradle-like 35 construction of said supports.

The foregoing and other novel features and functions will be apprehended as the herein description proceeds, and it will be obvious that modifications may be made in the disclosures 40 herein, without departing from the spirit hereof or the scope of the appended claims.

In the drawing:

Fig. 1 is a plan view of one form of the present improvement;

45 Fig. 2 is a sectional view taken on line 2—2, Fig. 1, looking in the direction of the arrows;

Fig. 3 is a fragmentary, enlarged, plan view of a coil support frame, modified over that shown 50 in Fig. 1;

Fig. 4 is a fragmentary sectional view taken on line 4—4, Fig. 3, looking in the direction of the arrows;

55 Fig. 5 is a fragmentary bottom view of the skeletal frame shown in Figs. 3 and 4;

Fig. 6 is a perspective view of a fragment of an aerocoil;

Fig. 7 is a fragmentary sectional view of a section of aerocoil showing a side view of Fig. 6; and

Fig. 8 is a reduced view, in elevation of a modified coil and mounting.

The device shown in Fig. 1 comprises a base plate 1, having three integral, upstanding in-curved arms 2, the upper edges thereof being joined by an annulus 3, which also, as seen in Fig. 2, partakes of the curve shown in the lower sectioned arm in Fig. 2. The curve of the arms 2, and rim 3, form a supporting seat for the coiled aerotube unit 4, which is first helically wound up in a straight cylindrical coil, and then the ends, at 4' and 4'', are brought together to form an annular coil, the diameter of the individually wound coils fitting the curve of the arms 2 and rim 3, as shown in the lower half of the section 20 of Fig. 2. The outer and inner diameters of the annular aerocoil are variable, and being flexible, like a coiled spring, the complete aerounit, or rosette, is snugly and contractedly held on the skeleton frame 1, 2 and 3.

The circular base 1 is provided near its outer perimeter with two apertures H and h, Fig. 1, h being shown dotted under rim 3, and through these two apertures, the ends 10 of each end of the aerorosette unit 4 are led across to the opposite side of the base, where the said ends 10 are connected to the aerolines leading to the electric alarm initiating means, or relay, in the well known manner, not shown. A recess R, Figs. 1 and 2, located in the under rim 5 of the base 35 permits the tube ends 10 to pass from in under the base in an undistorted line.

As a means for holding the aerounit 4 in its circular embrace in the skeleton frame 1—2—3, the adjacent opposite end coils 4' and 4'' are caught together with a suitable metal clamp, Figs. 6 and 7, said clamp comprising a bridge section 16, the elongate ends 17 of which are formed at right angles to the bridge piece 6, these being bent under the tubular end sections 4'—4'', as at 18—19, Fig. 6, and the bridge piece 16 may be bent down as in Fig. 7, and thus enclose the otherwise unconnected coil ends 4' and 4'', and thus hold the aerounit in annular assembly. 45 To mount the rosette or aerounit, it is merely sprung, or expanded open and placed in position. If it is desired to more firmly affix this rosette into its supporting frame, a wire W, Figs. 1 and 2, may be strung around the inside face of the coils 50 55

of the annulus 4, and the ends of the wire bound together.

In Figs. 3, 4 and 5, there is shown another form of skeleton aerocoil supporting frame, 5 which comprises a base 11, having an outer flanged rim 12, thus creating a recess 8 in the rear of the base. The central portion of the base is provided with a boss 6, which has a bore 7 therein whereby like the base 1, of Figs. 1 and 2, 10 the frame may be affixed to a wall or ceiling support, by a screw, not shown.

The base 11, Figs. 3, 4 and 5, is provided with 15 upstanding, spaced, integral, outwardly curved support arms 13, and these are joined at their upper ends by a circular rim 15. Intermediate 20 of the base 11 and rim 15 is located a circular reinforcing ring 14, which joins all of the arms 13. The inner face of ring 15 partakes of the 25 curve of the arms 13, and this curve is of the same dimensions as the transverse section of the wound aerotube coil 4. In placing a rosette like unit 4 in the frame or support of Figs. 3, 4 and 5, the coil unit 4 is compressed and entered in from the top, whereupon it then expands into the seat 25 formed by the arms 13, ring 14 and rim 15.

The support frame shown in Figs. 1 and 2, and in Figs. 3, 4 and 5, are both provided with tube retaining clamps 8, Figs. 2 and 5, said clamp being provided with offsets 8'-8", Fig. 5, at its 30 ends to provide a recessed seat for each tube end 10, the clamp being held to the base portions of the aerocoil bases by a screw 9.

Both aerocoil supports herein are made skeletal in form, hold the aero coils in annular and circular embrace, one of the coils embracing the aerocoil on the outer annular face, the other form embracing the aerocoil on its inner annular face. The form of support shown in Figs. 3, 35 4 and 5 is in the nature of an outer protective 40 armour and is useful in installations where the aerocoil is subject to accidental knocks or contacts, and thus is protective against accidental contacts which might collapse the tubing. Both forms of support give the tubing the maximum 45 exposure to the atmosphere and thus expose it to any temperature changes.

Another form of aerotube coil, possessing the same functions and features of the units shown in Figs. 1 and 3, is shown in Fig. 8, wherein the 50 aerotube unit 19 is in a single, coiled form, but is not formed into an annular construction, but is left in a straight helical form. The lowermost 55 terminal helice 20 has an integral uprising leg 21, which is bent to pass up through the center of the coil-unit 19, and is bent at right angles at its top, and is again bent, at right angles to form an aerotube extension 22, which is connected into the aeroalarm tube circuit not shown but understood.

60 The upper terminal helice 24 of the coil unit 19, is provided with an integral offset extension 23, which is arranged in a substantially parallel relation with the other extension 22, extension also being connected into the usual aeroalarm 65 circuit, not shown.

The straight coil unit 19 is held in operative position and supported by a U-shaped narrow metal bracket having a top transverse portion 28, and from which two downwardly extending 70 legs 25 and 26 depend, both legs being provided with opposed, right angled, short, coil supporting ends 27-27, at their lower ends, upon which the coil unit 19 rests. The upper transverse cross-bar 28, may be provided with a screw receiving 75 aperture 29, whereby the assembled, supported

coil 19 may be fastened to a wall or ceiling surface when in operative position. The aerocoil 19 is thus held, like previously described coil units 4 in such operative position as to be fully exposed to surrounding atmospheric conditions 5 with a minimum of atmospheric shielding effects. The structure of Fig. 8 may be vertically or horizontally suspended and is adapted to be installed under conditions not adapted for the installation of the forms of Figs. 1 and 3, but has the same 10 features, functions and advantages as described for Figs. 1 and 3.

Having thus described the invention what is claimed is:

1. A fire-alarm initiating means comprising a 15 substantially circular base; a ring spaced and parallel to the periphery of the base; a helically wound coil of aerotube having closely spaced windings, and having its axis annularly disposed parallel to said ring, the windings transversely 20 engaging said ring and periphery as seats and being disposed partly therebetween; and a wire in the coil in a plane between and parallel to said seats and engaging the inner face of the windings at the smallest diameter of the coil for 25 holding the coil on the seats.

2. A fire-alarm initiating means comprising a substantially circular base; a ring spaced and parallel to the periphery of the base; a helically wound coil of aerotube having closely spaced 30 windings, and having its axis annularly disposed parallel to said ring, the windings transversely engaging said ring and periphery as seats and being disposed partly therebetween; annular means in a plane between and parallel to said 35 seats and engaging the outer face of the windings at the largest diameter of the coil for holding the coil on the seats; and arms curved partly around the outer part of the coil and joining said ring, base and annular means for supporting 40 the ring on the base.

3. A fire-alarm initiating means comprising a substantially circular base having a peripheral flange and a screw opening; a ring spaced from and parallel to the periphery of the base on the 45 side opposite to the base; a helically wound coil of aerotube having closely spaced windings, said coil having its axis annularly disposed parallel to said periphery and ring, the windings transversely engaging both said ring and periphery 50 as seats and being disposed partly therebetween; the diameter of each winding being greater than the distance between the ring and periphery, the helix being disposed exterior to the ring and periphery; the periphery of said base being provided with oppositely disposed pairs of adjacent 55 openings, the tube at the ends of the helix being passed through one pair of openings against the back face of the base and then through the other pair; a clamp clamping together adjacent end 60 windings together; and a wire on the inside of the helix adjacent to the inner diameter of the coil, and having its ends secured together, for holding the coil against its seats.

4. In combination with the ceiling or wall or other support of a room, a fire-alarm initiating means comprising a circular base having a peripheral flange and a central screw opening by which the base is secured with said flange against the support by means of a single screw, leaving a 70 space between the base and support; a helically wound coil of aerotube having closely spaced windings, said coil having its axis annularly disposed parallel to the periphery of said base, the windings transversely engaging said base near 75

the periphery; the periphery of said base being provided with oppositely disposed pairs of adjacent openings, the tube at the ends of the helix being passed through one pair of openings against the back face of the base and then through the other pair.

5 5. A fire-alarm initiating means comprising a substantially circular base having a peripheral flange and a screw opening; a helically wound coil of aerotube having closely spaced windings, said coil having its axis annularly disposed parallel to said base, the windings transversely engaging the peripheral portion of the base; the periphery of said base being provided with oppositely disposed pairs of adjacent openings, the tube at the ends of the helix being passed through one pair of openings against the back face of the base and then through the other pair.

10 6. A fire-alarm initiating means comprising a substantially flat base adapted to be secured to a wall or ceiling; an aerotube having closely spaced windings, disposed on said base, the windings engaging said base, the windings being substantially all offset from the base on one side thereof whereby when the base is attached to a ceiling warmed air from a fire is directed by the ceiling to and through all of the windings.

15 7. A fire-alarm initiating means comprising a substantially flat base adapted to be secured to a wall or ceiling; a helically wound coil of aero-

20 tube having closely spaced windings, and having its axis substantially annularly disposed parallel to said base, the windings being substantially all offset from the base on one side thereof; and means for holding the coil on the base.

25 8. A fire-alarm initiating means comprising a substantially flat base; a helically wound coil of aerotube having closely spaced windings, and having its axis annularly disposed parallel to said base, the windings being offset from the base and transversely loosely engaging said base; and means loosely engaging the windings for holding the coil on the base.

30 9. A fire-alarm initiating means comprising a substantially flat base; a substantially ring-like member spaced and substantially parallel to the periphery of the base; a helically wound coil of aerotube having closely spaced windings, and having its axis annularly disposed parallel to said ring-like member, the windings transversely loosely engaging said member and periphery as seats and being disposed partly therebetween; and substantially annular means in a plane between and parallel to said seats and loosely engaging the windings for holding the coil from moving outwardly from the seats; whereby said coil is held on the base without the use of solder and may be easily and quickly detached from the base and mounted thereon.

WILLIAM J. KLEINKNECHT. 30
